UNITED STATES PATENT OFFICE

105,334

DESIGN FOR A POCKETKNIFE

Edward T. Mahoney, Milwaukee, Wis.

Application March 9, 1937, Serial No. 68,085

Term of patent 3½ years

To all whom it may concern:

Be it known that I, Edward T. Mahoney, a citizen of the United States, residing at Milwaukee, in the county of Milwaukee and State of Wisconsin, have invented a new, original, and ornamental Design for a Pocketknife, of which the following is a specification, reference being had to the accompanying drawing, forming part thereof.

Fig. 1 is a front perspective view of a pocketknife showing my new design; and

Fig. 2 is an elevational view of the opposite side of the knife disclosed in Fig. 1.

I claim:

The ornamental design for a pocketknife, as shown.

EDWARD T. MAHONEY.
